MECHANICAL PENCIL

Filed Sept. 26, 1923

UNITED STATES PATENT OFFICE

JOHN C. WAHL, OF CHICAGO, ILLINOIS, ASSIGNOR TO THE WAHL COMPANY, OF WILMINGTTON, DELAWARE, A CORPORATION OF DELAWARE

MECHANICAL PENCIL

Application filed September 26, 1923. Serial No. 664,896.

My invention relates to mechanical pencils and has for its primary object the provision of an automatic pencil whose lead propelling mechanism is such that when all or substantially all of the lead in the feed tube is exhausted through the tip, the said lead propelling mechanism may be withdrawn by direct longitudinal pull, thus eliminating the time wasting process of unscrewing the propelling mechanism after a lead has been exhausted from the tip.

Another object of my invention resides in providing an arrangement for permitting the lead propelling mechanism to be withdrawn from the barrel by a direct longitudinal pull only at a position when the lead propelling mechanism has reached its limit in the lead propelling direction of movement.

Still a further feature of the invention resides in the novel arrangement of lead holding chamber which is constructed and arranged so that the leads can be withdrawn without removing them endwise from the barrel after unscrewing the end cap as hereinbefore.

In the drawings—

Fig. 1 is a longitudinal sectional view of my invention, showing the feeding mechanism in position, and the crosshead in its uppermost position in the chamber.

Fig. 2 is a longitudinal sectional view showing the interior mechanism of the pencil, partially sectionally and partially fragmentally, with the lead propelling mechanism, consisting of the crosshead and the plunger at the lowermost extremity.

Fig. 3 is a longitudinal sectional view, partially sectionally and partially fragmentally.

Fig. 4 is a cross sectional view of line 4—4 of Fig. 2.

Fig. 5 is a perspective view of the interior mechanism of the pencil.

Fig. 6 is a perspective view of a portion of the interior mechanism, to be afterwards specifically described.

Fig. 7 is a cross sectional view of line 7—7 of Fig. 1.

The difficulty in the past with the Ever-sharp style of mechanical pencils has been

the slow and tedious loading process. It was necessary after the exhaustion of a lead from the tip to unscrew the mechanism from the barrel which necessitated the turning of the cap some 23 complete rotations to withdraw the said mechanism from the barrel, then unscrew the cap from the top of the reserve lead chamber, removing a lead, and the screwing of the cap back on the top of the reserve lead chamber.

The user next inserted the lead in the end of the lead feeding mechanism, pushed the lead feeding mechanism into the barrel, turning the cap in a clockwise direction until the crosshead in the lead feeding mechanism engaged the threads in the barrel and propelled the lead through the tip. This process consumes quite some time and three quarters of this time is eliminated in the structure hereinafter to be described.

The numeral 1 indicates an outer sheath or barrel, swedged at one end forming a small aperture, the opposite end being left open for the introduction of a lead feeding mechanism.

Numeral 2 broadly indicates a shell swedged at its lowermost extremity, as at 2^a, to form a lead holding member. The shell 2 has a thread 3 rolled therein extending from a short distance above the shoulders formed by the swedged end 2^a to a distance about midway between the said shoulder and the opposite end of the said tube.

Near the upper end of the tube 2 is formed a bead 4 which cooperates with the bead 5 rolled in the upper end of the barrel to prevent the tube 2 from being inserted too far into the barrel 1. The lower swedged end of the tube 2 is threaded as at 6 to receive female threads on the interior of the shank of the internally ribbed steel tip 7 commonly called a rifled tip. It is not deemed necessary to describe this rifled steel tip in detail except that it is that patented by Chas. R. Keenan, No. 1,151,016, August 24, 1915.

The tube 2 is inserted in the barrel until the bead 4 strikes bead 5. The steel tip 7 is screwed on to the feed tube 6 which projects through the aperture in the swedged end

thus locking the tube 2 in the barrel and preventing rotation thereof.

The lead feeding unit or mechanism consists of an actuator or tube 8 swedged at its lowermost end as at 9 to form an opening a little larger than the diameter of a writing lead and slotted as at 10. The slot is formed by splitting the shell and turning the edges of the split which form guide flanges for a crosshead that is adapted to ride in the said slot 10. This slot 10 extends from a position adjacent to the shoulder 11 formed by the swedging of the lower end 9 to a distance substantially midway between said shoulder and the opposite end of the tube 8. A rectangular shaped aperture 11' is punched in the said shoulder 11, the said aperture being punched directly below and in alignment with the slot 10.

20 The upper end of the tube 8 is threaded to receive an eraser holding member 12. Mounted in the actuator or tube 8 and extending through the rectangular shaped aperture 11 is a U shaped guide sleeve or channel member 13. This guide member has its flanges cut away for a portion of their length as at 14 to form retaining shoulders, and its end is beveled as at 15, for a purpose hereinafter made evident.

30 The bottom of the U-shaped guide or channel member 13 is provided with an opening or slot 16. This slot has an exact location relative to the beveled end 15 of the channel member as will be hereinafter made evident. In addition, the channel member is provided with a punched in detent or dimple 13' preferably located on one of the inner upstanding flanges. This dimple 13' is located a short distance to the rear of the slot 16.

40 The slotted channel member constitutes one embodiment of means to cause the release of the crosshead 17 from threaded engagement with the threads 3 of the inner tube 2 of the casing so as to permit the crosshead, its plunger and the actuator tube 8 to be withdrawn bodily rearwardly from the casing or barrel 1 by a direct rearward pull without the laborious unscrewing as heretofore.

50 This guide member 13 is adapted to be inserted into the tube 8 through the uppermost end thereof and is confined between a washer 27 hereinafter described and the lower conical shoulder 11 of the actuator tube 8. Preferably the beveled end 15 of this guide member 13 projects into the slot 11' in the shoulder 11 of the tube 8 to prevent the channel member from rotating within and relatively to the tube 8, that is, from being rotated within the tube and about its central axis 60 during the screwing of the actuator tube 8 by reason of the fact that the crosshead rests in the channel member and the tube and is in threaded engagement with and rotatable relatively to the barrel 1. Since the crosshead 65 thus projects into the walls of the slot 10 in

the actuator it must turn with the actuator. As thus held from rotational movement, the bottom of the member 13 constitutes a guideway for one edge of the crosshead while the threads 20 thereof are in threaded engagement 70 with the threads 3 on the inner wall of the tube 2. And it serves to maintain engagement between these threads on the crosshead and threads on the tube until automatically released by the registration of the slot 16 and 75 a correspondingly shaped adjacent portion of the crosshead.

80 A crosshead 17, having lateral projections 18 and 19, is provided. This crosshead is threaded on one edge as at 20, and on the opposite edge is smooth as at 30, and of a size to pass into the slot 16 of the channel member 13. Fitted in an aperture in the lower edge of said crosshead, and projecting therefrom is a plunger 21. The slot 10 in the tube 8 is spread and the plunger and crosshead are inserted therein, the feed wire being pushed through the swedged end 9.

85 The smooth edge 30 of the crosshead 17 is inserted between the flanges of the member 90 13. In this position the threads on the opposite edge project through the slot 10. The slot 10 is then squeezed together and the flanges therein slipped over the shoulders formed by the projections 18 and 19 on the 95 crosshead, and thus the crosshead and plunger are held in position in the tube 8, having free longitudinal movement with no rotary movement therein. As stated heretofore, the position of the crosshead inside the tube is such 100 that the threads 20 project beyond the peripheral edges of the slot 10 to engage the threads 3 of the inner wall of the tube 2.

105 The tube 8 has a longitudinally extending slot 22 stamped therein at its upper end.

Reverting now to the function of the slotted channel member 13 as a means for permitting disengagement of the crosshead 17 from threaded engagement with the tube 2 it must be manifest that if the channel member were 110 immobile endwise in the actuator tube 8 or if for instance the slot 16 were formed directly in the wall of the actuator at the desired spaced relation from the conical shoulder 11 thereof, the crosshead 17 would always be 115 free to drop into this recess whenever the crosshead was positioned opposite this location of the slot. For instance, if the actuator were withdrawn from its position shown in Figure 1 to that position shown in Figure 3, 120 wherein the crosshead is still in threaded engagement with the threads 3 of the tube 2, then if the slot 16 were in its same position shown in Figure 1, the crosshead would register with slot 16 and would disengage from the barrel 1 at this point. This is objectionable. Therefore, to provide an arrangement wherein the crosshead will release from threaded engagement with the barrel only at 125 the extreme advanced position of the cross 130

head and actuator within the barrel, which corresponds to the exhausted condition of the lead in the tip, the slot 16 is formed in the channel or guide member 13 and the latter is constructed and arranged to shift in the actuator tube to automatically position the slot 16 either into registry with the advanced position of the crosshead when the actuator is also in advanced position, which is disclosed in Figure 2, or to automatically position the slot 16 out of registration with any inward position of the crosshead in the actuator tube 8 as is shown in Figure 3.

To this end the guide member 13 is preferably made slightly shorter than the distance between the washer 27 and the conical shoulder 11 of actuator tube 8 so that the guide member can slide endwise therein. And since the beveled nose 15 of the guide member 13 projects through the slot 11^a of the shoulder 11, the guide member is free to shift endwise in this direction until the shoulders 14 thereon contact with the walls of the slot 11^a. In this position the channel member will be in extreme forward position with the beveled nose 15 projecting some distance through the slot 11^a as illustrated in Figures 3 and 5. This shifted position carries the slot 16 so far forwardly toward the conical shoulder 11 that it is out of registration with any possible extreme forward position of the portion 80 of the crosshead. Hence no release can take place.

The beveled nose 15 of the channel member insures the proper positioning of this slot to effect registration. For instance, if the actuator is in the position shown in Fig. 3, with the nose 15 projecting through slot 11^a when the actuator is pushed forwardly to the position shown in Figure 1 the nose 15 will at once contact with the conical wall 2^b of the tube 2, thus shifting the channel member 13 rearwardly the correct distance to reposition the slot 16 at a place where it will release the crosshead when the latter reaches its releasing position, Figure 2.

A simple arrangement for automatically shifting the channel member forwardly in the actuator tube 8 to carry the slot 16 beyond crosshead registering position is provided by the indent or dimple 13' in the inner wall of the channel member.

Considering once more the position of the pencil as shown in Figure 1 with the cross-head 17 in threaded engagement with the upper threaded zone 3 of the barrel 2, if it be desired to pull out the actuator tube 8 into the position shown in Figure 3 while still maintaining the threaded connection between the crosshead 17 and the barrel it will be noted that as the actuator 8 is withdrawn the crosshead 17 will remain stationary relative to the barrel 2. But the actuator, including the channel member 13, will be drawn rearwardly past the crosshead. During this

movement the dimple 13' on the side of the channel member in the actuator will come into contact with the crosshead 17 and the channel member will be held slightly from further rearward movement while the actuator 8 continues to move rearwardly. This shifts the channel member 13 forwardly of the actuator 8 so that the nose 15 of the member passes through the slot 11' in the shoulder 11 of the actuator as shown in Figure 3. This is the nonregistering position of the slot 16. It will be noted that the conical shoulder 11 is now withdrawn from its nesting shoulder 2^b of the casing so that there is no abutting wall 2^b to prevent the projecting of the nose 15.

This indent 13' does not extend inwardly so far as to prevent the crosshead passing it when the nose 15 is finally pushed rearwardly by the conical shoulder 2^b when the actuator 8 and crosshead 17 are finally screwed to extreme advanced position as in Figure 2. At this time the indent will permit the crosshead to frictionally pass by, in either case the crosshead 17 when engaging the indent 13' will drag the channel member along with it the required slot positioning distance until the one end of the channel member contacts either against the washer 27 or the opposite shoulder 14 contacts against the wall of slot 11' or the nose 15 against the conical shoulder 2^b. After this contact the crosshead frictionally passes the detent 13'.

The tube 8 has a longitudinally extending slot 22 stamped therein at its outer end. This slot is preferably substantially triangular in shape with the apex of the triangle disposed at the outer end of the tube. A sleeve 23 loosely fits around tube 8 and is capable of slight endwise movement on the tube as well as angular movement thereon. This sleeve 23 has a corresponding slot 24 stamped therein and of similar shape. These slots are adapted to be registered when the sleeve is shifted to a predetermined position. A diagonally extending aperture 25 is stamped in the tube 8 and an indent 26 is formed in the tube 23 to project into the opening 25. This aperture 25 and detent 26 constitute a simple means for limiting the endwise and angular shifting of sleeve 23 on the tube 8 for determining the proper opening and closing positions of the relatively shiftable slots. It must be manifest that by rotating the sleeve 23, the apertures 22 and 24 may be aligned to permit lead being withdrawn from the lead chamber formed in the upper portion of the shell 8. This lead channel is segregated from the lower part of the feeding mechanism by means of a washer 27 which is spun in the tube directly back of the slot 10.

Due to the triangular shape of the slots 22 and 24 the lead will be projected more easily outwardly as illustrated in Figure 5. This is due to the smallness of the slot at the apex, 130

which is slightly rounded and of sufficient width to permit a single lead to project therethrough, while the gradually increasing size of the aperture upwardly from the apex permits such single lead to roll more quickly into projecting position. In other words the larger upper opening expedites the projection of the single lead from the aperture.

A cap 28 is provided to slip over the member 12, thus forming a cover for the eraser 29, and a grip means whereby the interior mechanism may be rotated to propel the lead.

The operation of the device is as follows:

A lead is inserted in the small aperture 15 formed by the swedging of the end 9, the barrel is inserted over the feeding mechanism until the threads 20 of the crosshead 17 strike the threads in the tube 2, whereupon the feeding mechanism is rotated in a clockwise direction and the crosshead and the plunger 21 will advance forwardly propelling the lead through the lead holding member 2^a thru the aperture in the end of the tip to writing position.

When the crosshead and the plunger have expelled practically all of the lead the crosshead will be in the lower end of the threaded portion of the shell 2, and in the lower end of each of guide 13 and the tube 8. A lug 30 30 formed on the smooth face of the crosshead 17 drops into the aperture 16 in the tube 13, thus causing the threads on the crosshead to disengage from the threads in the tube 8. The feeding mechanism may then be withdrawn 35 from the barrel by a mere longitudinal pull and new lead may be inserted by turning the sleeve 23 and removing a new lead through apertures 22 and 24, and the pencil reloaded as heretofore described.

Applicant wishes to particularly point out that although the feeding mechanism may be withdrawn from the barrel when the lead has been entirely expelled from the pencil, that in no other position during the feeding 45 operation may the said feeding mechanism be withdrawn from the barrel by means of longitudinal pull. In other words, the barrel and the pencil are attached together until all of the lead has been expelled from the pencil. The pencil and mechanism may be freely rotated at that point without injury to the mechanism.

Many departures from and variations may be made in the specific structure herein shown 55 without departing from the spirit of my invention, the scope of which is to be determined in the appended claims.

Having described my invention, what I desire to secure by Letters Patent in the U. S.

Patent Office is:-

1. A mechanical pencil comprising a casing, a lead feeding plunger, means for imparting movement to said plunger, and a guide member normally maintaining the plunger in engagement with said movement

imparting means, throughout the major portion of its travel, said guide member being constructed to release the plunger from said engagement only at the limit of its lead feeding movement.

2. A mechanical pencil comprising a casing, a lead feeding unit movable within the casing, means for causing the unit to travel within the casing, and a guide member normally maintaining said unit in engagement with its travel causing means, throughout the major portion of its travel, said guide member being constructed to release the unit from said travel causing means only at the limit of its lead feeding travel.

3. A mechanical pencil comprising a casing, a lead feeding plunger, means for imparting movement to said plunger, and a guide member having means constructed to hold said plunger and its movement causing means in engagement until said plunger has moved in one direction to a predetermined position, whereupon said plunger may be withdrawn from said position by a straight

pull. 90
4. A mechanical pencil comprising a casing, a lead propelling means, said casing and said means having complementary engaging parts by means of which said propelling means may be caused to travel, and a guide member acting to normally maintain engagement of the casing and lead propelling means throughout the major portion of the travel of the latter, and constructed to permit disengagement thereof when the lead propelling member reaches a predetermined position. 95
100

5. In a mechanical pencil the combination of a casing having a threaded portion and a tip, a plunger carrying member, and means for normally maintaining engagement of said member with the threaded portion of the casing, whereby said member may be caused to travel within the casing to advance a lead through said tip, said plunger carrying member being releasable from said threaded portion only when said member reaches a predetermined position in its travel. 105
110

6. In a mechanical pencil the combination of a casing having a threaded portion and a tip, a plunger carrying member, and means for normally maintaining engagement of said member with the threaded portion of the casing, whereby said member may be caused to travel within the casing to advance a lead through said tip, said engagement maintaining means having a portion arranged to cooperate with said plunger-carrying member to effect disengagement of said casing and said plunger carrying member. 115
120

7. In a mechanical pencil the combination of a casing having a threaded portion and a tip, a plunger carrying member, and means for normally maintaining engagement of said member with the threaded portion of the casing, whereby said member may be caused 125
130

to travel within the casing to advance a lead through said tip, said engagement maintaining means having a portion disposed in the path of travel of said plunger-carrying member to permit disengagement of said member and said casing at a predetermined position in the travel of said member.

8. In a mechanical pencil, the combination of a casing having a threaded portion and a tip, a plunger in said casing having a cross-head adapted to engage said threaded portion and mounted for endwise and bodily lateral movement relative to said casing, and means in said casing constructed to prevent the lateral movement of said crosshead until it reaches a predetermined position in its endwise movement.

9. In a mechanical pencil, the combination of a casing having a threaded portion and a tip, a plunger in said casing having a cross-head adapted to engage said threaded portion, an actuator adapted to operate said crosshead to cause said crosshead and plunger to advance relative to the casing whereby to propel the lead through the tip, means carried by said actuator constructed to lock said crosshead and threaded portion in propelling engagement, said means being movable relative to said actuator to release said propelling engagement.

10. In a mechanical pencil, the combination of a casing having a threaded portion and a tip, a plunger in said casing having a crosshead adapted to engage said threaded portion, a movable actuator adapted to operate said crosshead to cause it and the plunger to advance relative to the casing and propel the lead through the tip, means movably mounted in said actuator for locking said crosshead and threaded portion in propelling engagement, said means being constructed and arranged to automatically unlock said crosshead and threaded portion at a predetermined point in the movement of said crosshead.

11. In a mechanical pencil, a casing, a lead feeding plunger, means for imparting a feeding movement to said plunger, and a guide member carried by a movable portion of the feeding means for maintaining a normal engagement between the plunger and the casing, said guide member being constructed to permit disengagement of the parts effecting lead feeding movement when the plunger reaches a predetermined position.

12. In a mechanical pencil, the combination of a casing having a threaded portion and a tip, a plunger in said casing having a crosshead adapted to engage said threaded portion, a movable actuator adapted to operate said crosshead to cause the plunger to advance relatively to the casing whereby to propel the lead through the tip, a substantially U-shaped channel member mounted on said actuator and adapted to receive a por-

tion of said crosshead so as to maintain the latter in propelling engagement with said threaded portion, said channel member having a cut-away portion disposed to permit the disengagement of said crosshead and threaded portion.

13. In a mechanical pencil, the combination of a casing having a threaded portion and a tip, a plunger in said casing having a cross-head adapted to engage said threaded portion, a movable actuator adapted to propel the crosshead to extreme forward position and to propel said lead substantially entirely through said tip, a channel member movably mounted on said actuator and adapted to receive said crosshead so as to maintain the latter in propelling engagement with said threaded portion, said member having a cut-out formed therein to permit said crosshead to disengage from said threaded portion when said crosshead is in forward position, said channel member having a portion adapted to contact with said casing to thereby insure the correct positioning of said cut-out opposite the forward position of said crosshead.

14. In a mechanical pencil, the combination of a casing having a threaded portion and a tip, a plunger in said casing having a cross-head adapted to engage said threaded portion, a movable actuator adapted to dispose the crosshead in extreme forward position to propel said lead substantially entirely through said tip, a channel member movably mounted on said actuator and adapted to receive said crosshead so as to maintain the latter in propelling engagement with said threaded portion, said channel member having a cut-out formed therein to permit said crosshead to disengage from said threaded portion when said crosshead is in forward position, said channel member having a portion adapted to contact with said casing in the forward position of the crosshead, to thereby insure the correct positioning of said cut-out opposite the forward position of said crosshead, and said member having a portion adapted to yieldably engage with said cross-head to be shifted thereby to carry said slot beyond crosshead registering position.

15. In a mechanical pencil, the combination of a casing having a threaded portion, a plunger operative in said casing and having a crosshead adapted to engage said threaded portion to propel the lead, an actuator in said casing adapted to propel the crosshead longitudinally of the casing, a guide member adapted normally to cause interlocked driving engagement between said crosshead and threaded portion, a slot in said guide member adapted to register with said crosshead at a certain position to release said interlocked driving engagement, and means on said guide member cooperating with said crosshead normally to shift said guide member to prevent registration of said slot and crosshead.

16. In a mechanical pencil the combination of a casing having a threaded portion, a plunger operative in said casing and having a crosshead adapted to engage said threaded portion to propel the lead, an actuator in said casing adapted to propel the crosshead longitudinally of the casing, a guide member adapted normally to cause interlocked driving engagement between said crosshead and threaded portion, a slot in said guide member adapted on predetermined relative positions of said crosshead and guide member to register with said interlocked driving engagement, said guide member having a yieldable detent thereon arranged in the path of movement of said crosshead whereby to shift said guide member on certain other relative positions of said crosshead and guide member to prevent registration of said slot and crosshead.
17. In a mechanical pencil, the combination of a casing, a lead propelling mechanism therein provided with driving mechanism for engaging said casing to propel the lead, a member movable with and relative to said propelling mechanism and provided with means for releasing said driving engagement between said casing and propelling mechanism, and means to cause said member to move relatively to said propelling mechanism to prevent the release of said driving engagement.
18. In a mechanical pencil, a holder, and means associated therewith for propelling a lead, said propelling means comprising relatively rotatable actuating and cooperating feeding means, and means operable only at approximately the termination of the lead propelling movement to break the operative connection between the lead propelling instrumentalities to permit withdrawal of at least a portion thereof from the holder by a direct longitudinal pull, said last mentioned means comprising a longitudinally shiftable element compelling the operative connection during the propelling movement, but permitting relative recession of said instrumentalities at the breaking point, and means for effecting the longitudinal shifting of said element.
19. In a mechanical pencil, a holder, and means associated therewith for propelling a lead, said propelling means comprising a relatively rotatable threaded sleeve and cooperating threaded feeding head, and means operable, only at approximately the termination of the lead propelling movement to break the operative connection between the sleeve and head to permit withdrawal of the head and immediately associated parts from the holder by a direct longitudinal pull, said last mentioned means comprising a longitudinally shiftable element compelling the operative connection during the propelling movement but permitting relative recession of said
- head and sleeve at the breaking point, and means for effecting the longitudinal shifting of said element.
20. A mechanical pencil comprising a casing, lead feeding means including a plunger operatively associated with the casing for movement longitudinally thereof, and a guide normally maintaining the plunger in engagement with the casing throughout the major portion of its travel, said guide being constructed to release the plunger only at the substantial limit of its lead feeding travel.
21. A mechanical pencil comprising a casing and lead feeding means operatively associated with the casing, a guide adapted to maintain operative connection between said casing and lead feeding means during feeding movement of the latter, said guide being constructed and arranged to release the lead feeding means only at the substantial end of its lead feeding movement.
22. In a pencil a casing having a threaded part, a lead feed unit therein comprising a lead feed actuating member rotatably associated with the casing and a plunger having a portion coacting with the threads of the casing for moving the plunger longitudinally of said casing upon rotation of said actuating member, release means associated with said plunger, and means associated with the casing for effecting operation of the release means to cause release of the lead feed unit from the casing when the plunger has substantially reached its limit of lead discharging travel.
23. A pencil comprising a casing having a threaded part and a lead feed unit having a portion coacting with the threaded portion of the casing, release means carried by said lead feed unit, and means carried by the casing to project into the path of said release means to operate the same to cause release of the lead feed unit from the casing when the lead feed unit has substantially reached its limit of lead discharging operation.
24. In a mechanical pencil the combination of a casing having a threaded portion, a feed unit removable from the casing for loading, said unit having means operatively connecting it with the threaded portion of the casing during and until the feeding of the lead is practically completed, and means for causing release of said connection when the feeding of the lead is substantially completed.
25. In a mechanical pencil, the combination of a casing, a lead feed unit therein and having a part adapted to rotate relatively to the casing and a part adapted to engage the casing and be moved longitudinally of the casing by rotation of said first mentioned part, and releasing means carried by the rotating part and operative to engage a part on the casing to release engagement of the longitudinally movable part from the

casing so as to permit the withdrawal of the lead feed unit from the casing by a straight longitudinal pull.

26. In a mechanical pencil, the combination of a casing, a lead feed unit therein and having a rotary part and a longitudinally movable part adapted to engage the casing, and means carried by the rotary part and movable relatively thereto and to release the longitudinally movable part from the casing to permit withdrawal of the feed unit from the casing upon a straight longitudinal pull.

27. In a mechanical pencil, the combination of a casing, a lead feed unit therein and having a rotary part and a longitudinally movable part adapted to engage the casing, and means carried by the rotary part and movable relatively thereto by contact with a part of the casing for automatically releasing the feed unit from the casing.

28. In a mechanical pencil, the combination of a casing having a threaded part, a lead feed unit therein adapted to rotate relative to the casing, a lead propelling member carried by said unit and having a threaded part engaging the threaded portion of the casing, for causing the lead propelling member to be advanced by the rotation of said unit, a device carried by the lead feed unit adapted to engage the lead propelling member to maintain its engagement with the threaded portion of the casing during certain portions of the travel of the threaded part of the propelling member, said device being constructed and arranged to cause the automatic disengagement of said threaded parts at a definite point of the travel of the threaded part of the propelling member and means for preventing the automatic disengagement of said threaded parts at any other point in the travel of said threaded part of the propelling member.

29. In a mechanical pencil, the combination of a casing having a thread, a lead feed unit therein comprising an actuator rotatably engaging the casing and carrying a cross-head adapted to engage the thread of the casing for feeding the lead through the casing on rotation of the actuator, an automatic release shiftably carried on the actuator and engaging the crosshead to maintain it in engagement with the thread of the casing, said release having a portion arranged to cause the disengagement of the crosshead from the casing thread at a definite point in its travel, said release having a portion adapted to be engaged by the casing to shift the automatic release in one direction and having another portion adapted to be engaged by the crosshead to shift the automatic release in the opposite direction.

30. In a mechanical pencil, the combination of a casing having a thread, a lead feed unit therein having a rotary part and a trans-

latable cross-head adapted to engage the thread of the casing, and an automatic releasing device for the crosshead having a resilient part adapted to be engaged by the crosshead to cause movement of the device, 70 said resilient part permitting the crosshead to move past the resilient part in its operative travel.

31. In a mechanical pencil, the combination of a casing having a thread, a lead feed unit therein having a rotary part and a translatable crosshead adapted to engage the thread of the casing, and a channel-shaped sheet-metal guide having a slot near one end, a nose adjacent thereto and an indent adjacent the slot, said slot permitting the crosshead to pass thereinto to release from the casing thread, said nose being adapted to project through an aperture in the rotary part of the feed unit to be contacted by the casing 85 to shift the guide in one direction and said indent being adapted to be contacted by the crosshead to cause the shifting of the guide in another direction, said indent being resilient to permit the passage of the crosshead. 90

32. In a pencil the combination of a threaded casing, a lead feed unit associated therewith comprising an actuator rotatably mounted in said casing, a cross-head movable in said actuator between two extreme positions and engaging the threads of the casing, a guide adapted to move in the actuator between two extreme positions and relative to the cross-head, said guide having a slot adapted to register with the cross-head only when the 100 actuator and cross-head are in extreme forward position at the front portion of the casing and means to prevent the slot in the guide registering with the cross-head in any other positions of the actuator, cross-head and 105 guide.

In witness whereof I have hereunto subscribed my name.
